CLAIM

The ornamental design for a storage rack for sterile packaging, as shown and described.

DESCRIPTION

FIG. 1 is a top, front, and right perspective view of a storage rack for sterile packaging in accordance with our new design, used in an environment showing a bridging element containing signage;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top, front and right perspective view of a storage rack for sterile packaging in accordance with our new design, showing the environment removed;

FIG. 9 is a top plan view thereof;

FIG. 10 is a bottom plan view thereof;

FIG. 11 is a left side elevational view thereof;

FIG. 12 is a right side elevational view thereof;

FIG. 13 is a rear elevational view thereof; and,

FIG. 14 is a front elevational view thereof.

The dashed broken lines in the drawings depict portions of the storage rack for sterile packaging that form no part of the claimed design.

The dot-dash broken lines depict the boundaries of the claim and form no part thereof.

The dot-dot-dash broken lines in the FIGS. 1-7 depict environmental subject matter and form no part of the claimed design.
